HIS ATTORNEYS.

UNITED STATES PATENT OFFICE.

CHARLES E. ROBERTS, OF OAK PARK, ILLINOIS.

DESIGN FOR A DUST-CAP.

SPECIFICATION forming part of Design No. 25,828, dated July 21, 1896.

Application filed June 4, 1896. Serial No. 594,829. Term of patent 7 years.

To all whom it may concern:

Be it known that I, CHARLES E. ROBERTS, a citizen of the United States, residing in Oak Park, in the county of Cook and State of Illinois, have invented and produced a new and original Design for Dust-Caps for Ball-Bearings, of which the following is a specification.

Figure 1 is an edge view of a dust-cap, showing my design. Fig. 2 is a front elevation of 10 the same, and Fig. 3 a sectional view, these views being deemed necessary to fully illustrate my design.

The leading feature of my design consists 15 in the deep annular recess formed between the margin or rim and the center of the cap upon the front or vertical surface thereof.

In the drawings, A represents the rim or 20 margin of the dust-cap, which is circular in its general contour, and B represents the center of the cap and is many-sided, as plainly

shown. Between this rim and the center B is the recess referred to and indicated by the letter C. The recess is deep and the sides of the rim and center which form its walls are nearly parallel. The face of the center B 25 may be slightly rounded. The base of the cap (shown at D) is threaded and when in use will be covered from view, and therefore forms no part of the design.

This cap is made of metal, and when plated 30 presents a very pleasing and ornamental appearance.

I claim—

The design for dust-caps for the wheel-bearings of vehicles, substantially as shown.

CHARLES E. ROBERTS.
